(57) **CLAIM**

The ornamental design for an electrical fan housing, as shown and described.

DESCRIPTION

FIG. 1 is a top, front and left side perspective view of an electrical fan housing in accordance with invention;

FIG. 2 is a front view thereof;

FIG. 3 is a top plan view thereof;

FIG. 4 is a right side view thereof that is identical/symmetrical to the left side view thereof; and,

FIG. 5 is a rear view thereof.

The bottom is plain and not ornamental.

The broken line showing of environmental structure in FIGS. 1-5 is for illustrative purposes only and forms no part of the claimed design.
